A. PFLANTZER

GARMENT SUPPORTER

Filed March 19, 1924

Fig. 1

UNITED STATES PATENT OFFICE.

ABRAHAM PFLANTZER, OF NEW YORK, N. Y.

GARMENT SUPPORTER.

Application filed March 19, 1924. Serial No. 700,218.

My invention relates to garment holders for general use. It relates more particularly to such a garment holder in which a fabric will be firmly and positively held. It further relates to such a garment holder in which the finest fabric will not be injured by its constant use.

I have shown my garment holder as clamping and holding two separate fabrics, as for example the top of a stocking and a corset; though, of course, it may be used to clamp different portions of the same material, for example, as a sleeve holder to shorten the length of a sleeve.

My invention further relates to certain articles of manufacture, combinations, and details of construction to be more fully hereinafter described and pointed out in the claims.

In the accompanying drawings the same reference numerals refer to similar parts in the several figures.

Fig. 1 is a side elevation, partly in vertical section, showing the preferred form of my garment supporter with the jaws closed and firmly gripping two fabrics;

Fig. 2 is a side elevation the same as Fig. 1, partly in vertical section with the jaws open ready to clamp the interposed fabrics;

Fig. 3 is a vertical section on the line 3-3 of Fig. 1;

Fig. 4 is a detail plan view of one of the clamping members;

Fig. 5 is a modification in which the two clamping members are rigidly secured together;

Fig. 6 is a detail side elevation, partly broken away, to show a different manner of constructing the clamping members.

My garment supporter is essentially a duplex supporter 1 having a plurality of clamping members 2 and 3 connected together, preferably by means of a coil spring 4.

Each of the clamping members has a rigid base 5 with a countersunk recess 6 within which is mounted a pad of resilient material 7, preferably rubber. Formed integral with the rigid base 5, or separate therefrom and secured to it as shown in Fig.

6, is a rigid semi-circular member 8 to which is pivoted a link 9 on the pivot 10. The other end of this link 9 is pivoted at 11 by means of the pin 12 to the movable jaw 13. On the same pin 12 is pivoted one end of a toggle link 14, the other end of which is pivoted at 15 to the bell crank lever 16 pivoted at 17 to

the rigid semi-circular member 10. This bell crank lever 16 has a handle 18 which normally rests within a slot 19 in the rigid semi-circular member 8 when the silk, or any other fabric 20, is firmly, immovably and positively clamped between the resilient pad 7 and the resilient pad 21 carried by the movable jaw 13, Fig. 1.

When the parts are in the position shown in Fig. 1, the end of the lever 18 is pressed down so as to lie substantially within the slot 19, though it can be readily freed by pressing the finger into the opening 22, beneath the handle 18 of the bell crank lever 16 so that a slight outward pressure by the finger will rock the bell crank lever 16, break the toggle and permit the withdrawal of the fabric 20, the resiliency of the pads 7 and 21 being such as to free the fabric the moment that the end of the bell crank lever 18 is moved out sufficient to break the toggle. The movable jaw 13 may be further raised by pressing up on the bell crank lever 16 to bring the parts into the position shown in Fig. 2.

The complementary clamping member 3 is provided with duplicate, fixed and movable jaws to grip the fabric 23 which may be secured to a corset of the user, or this fabric 23 may be secured to any other garment. When this fabric 23 is secured to the corset the stocking 20 is supported in position without any fear or liability that the parts will slip or that constant usage will weaken or mar the fabric. It will further be noted that my locking jaws act positively, there being no spring action, except such as is due to the compression of the resilient pads 7 and 21; when this compression is released the resilient pad 7 will move the movable jaw 13 a sufficient distance to permit the ready removal of the fabric 20 or 23, as the case may be.

While I have described the two fabrics shown in Fig. 1 as being of different material, and portions of different garments, my garment supporter can of course be used to clamp different portions of the same fabric, as for example a sleeve, to shorten it; or it may be used in any other position.

In the form shown in Figs. 1 and 2 the coil spring 4 permits the different clamping members to be moved relatively with relation to each other, to take up a sudden jar or strain. In Fig. 5 I have shown a pair of my clamping jaws rigidly secured together by means of a plate 25 and screws 26, 26

instead of employing the resilient spring 4. In some cases instead of having the rigid base 5 and the rigid semi-circular member 8 integral I may form these separate and secure them together by means of a screw 27, as shown in Fig. 6.

Having thus described this invention in connection with illustrative embodiments thereof, to the details of which I do not desire to be limited, what is claimed as new and what is desired to secure by Letters Patent is set forth in the appended claims.

What I claim is:—

1. A garment holder comprising a fixed jaw, a resilient pad mounted in the fixed jaw, a movable jaw, and means including a toggle lever pivoted to the movable jaw to positively lock the movable jaw against the fixed jaw and at the same time compress more or less the resilient pad carried by the fixed jaw.
2. A garment holder comprising a fixed jaw, a resilient pad mounted in the fixed jaw, a jaw movable to successively parallel positions toward and away from the fixed jaw, a resilient pad carried by the movable jaw, and means to positively lock the movable jaw against the fixed jaw and at the same time compress more or less the resilient pads carried by the fixed and movable jaws.
3. A garment holder comprising a fixed and movable jaw and toggle means one arm of which is pivoted to the movable jaw to positively lock them in clamping position.
4. A garment holder comprising a fixed jaw, a resilient pad carried by the fixed jaw, a movable jaw, a resilient pad carried by the movable jaw, a toggle link supporting the movable jaw, and a toggle lever adapted to operate the toggle link to clamp the two jaws together.
5. A garment holder comprising a clamping member provided with a fixed jaw, a rigid semi-circular member secured to the fixed jaw, a movable jaw mounted within the rigid semi-circular member, and means to positively lock the movable jaw against the fixed jaw.
6. A garment holder comprising a clamping member provided with a fixed jaw, a

rigid semi-circular member secured to the fixed jaw, a movable jaw mounted within the rigid semi-circular member, and a toggle carried by the rigid semi-circular member adapted to positively lock the movable jaw against the fixed jaw.

7. A garment holder comprising a clamping member provided with a fixed jaw, a rigid semi-circular member secured to the fixed jaw and provided with a slot, a movable jaw mounted with the rigid semi-circular member, a toggle link secured to the movable jaw, a toggle lever pivoted on the rigid semi-circular member and having a handle adapted to lie in the slot of the rigid semi-circular member.

8. A garment holder, comprising in combination relatively movable clamping jaws, one of which is slotted, toggle means for moving one of the jaws, and an operating lever connected to the toggle means for operating it, pivoted to the slotted jaw and adapted to be seated in the slot of said slotted jaw.

9. A garment holder, comprising in combination relatively movable clamping jaws, one of which has a gripping face of resilient material, toggle means for moving one of the jaws to successively parallel positions, toward and away from the other jaw, and means for locking the movable jaw in clamping position.

10. A garment holder, comprising in combination relatively movable clamping jaws, toggle means for moving one of the jaws to successively parallel positions, toward and away from the other jaw, and means for locking the movable jaw in clamping position.

11. A garment holder, comprising in combination relatively movable clamping jaws, means including toggle mechanism and a bell crank for moving one of the jaws to successively parallel positions, toward and away from the other jaw, and means for locking the movable jaw in clamping position.

In testimony whereof, I have signed my name to this specification.

ABRAHAM PFLANTZER.
